UNITED STATES PATENT OFFICE.

HEBER C. GRIFFIN, OF FRANKLIN FALLS, NEW HAMPSHIRE, ASSIGNOR TO
THE GRIFFIN LOCK COMPANY, OF SAME PLACE.

COMBINATION-LOCK.

SPECIFICATION forming part of Letters Patent No. 381,068, dated April 10, 1888.

Application filed December 17, 1887. Serial No. 258,158. (Model.)

To all whom it may concern:

Be it known that I, HEBER C. GRIFFIN, a citizen of the United States, residing at Franklin Falls, in the county of Merrimac and State of New Hampshire, have invented certain new and useful Improvements in Combination-Locks, of which the following is a specification.

This invention relates to most any form of combination-lock, and is designed to facilitate the finding by the operator of the point from which to compute the combination, commonly called "zero."

The object is to enable the operator to find zero wholly by the sense of feeling, as well as count the revolutions of the knob. This is readily accomplished by the device illustrated in the accompanying drawings, and clearly described in the following specification and claims, of which said drawings form an inseparable part.

Figure 1 is a perspective view showing a portion of the edge and front or outside of a door to which a lock and my improved operating-spindle are attached. Fig. 2 is a similar view having a portion of the outside of the door broken away and exposing to view the lock-housing. Fig. 3 is a sectional elevation showing a portion of the lock-housing, its rotative tumblers, and my improved operating-spindle as when in its normal position. Fig. 4 is a similar view showing the improved operating-spindle as when at zero. Fig. 5 illustrates a simple modification of a portion of my improved operating-spindle.

Similar reference-letters indicate corresponding parts throughout the various views.

A is a portion of the inner part of a lock-housing, and a is an integral journal on which the rotative tumblers rest, which also serves as a bearing for my improved operating-spindle, through which it passes.

The latter is formed in two parts, B C, one end of the spindle portion B being adapted to enter the knob portion C, which is bored to form a loose fit, and rendered capable of longitudinal movement thereon in the following manner, viz: The spindle portion B is slotted at b, and the knob portion C is provided 50 with a hole, c, which passes through it trans-

versely and a little to one side of its longitudinal center, accommodating a pin, c', which passes through the said slot in the spindle portion B. A spiral spring, D, may be placed in the chambered portion of the knob portion C, bearing against the outer end of the spindle portion B, as shown, and thus hold said knob portion C as shown in Fig. 3—i. e., with the pin c' bearing against the outer end of the slot b of the said spindle portion B—for a purpose 60 to be hereinafter explained. The said spindle portion B may be shouldered at b' against the lock-housing A, or otherwise prevented from further entering the lock.

In connection with my improvement it is 65 necessary that a stop-piece, a', be provided on the lock-housing A at a point to contact with a slot, c', formed for this purpose in the inner face of the knob portion C of my improved spindle, which designates the starting-point 70 for computing the combination. This stop-piece a' may be semicircular, as in Figs. 2, 3, 4, or a thin projecting lug, as in Fig. 5, provided always that the slot c' of the knob portion C shall be of corresponding length, in 75 order that there may be no lost motion when said knob portion is engaged with said stop-piece a'.

To find zero by the use of this improved spindle, it is but necessary to press the knob portion C inward while rotating the same, and the moment the slot c' and stop-piece a' are opposite the knob portion yields to the pressure and receives the said stop-piece a', as in Fig. 4. Then by relieving the pressure the knob portion of the spindle may be turned for computation.

Having described my improvement, what I claim, and desire to secure by Letters Patent of the United States, is—

1. The combination, with a combination-lock, of an operating-spindle composed of two parts, one movable longitudinally upon the other and rotative only in unison therewith, and a suitable spring whereby said movable member is held in its normal position, substantially as and for the purpose explained.

2. The combination, with the lock-housing having a projection or stop-lug near the operating-spindle, the said spindle, a knob or

handle portion for rotating the same capable of longitudinal movement thereon, and provided with a slot for engaging the stop-lug on said lock-housing, and a suitable spring whereby said movable knob is held normally clear of the said stop-lug, all substantially as and for the purpose set forth.

In testimony whereof I affix my signature in presence of two witnesses.

HEBER C. GRIFFIN.
